DESIGN FOR SAFETY PAPER OR ARTICLE OF SIMILAR NATURE

John H. Harland, Atlanta, Ga., assignor to John H. Harland Company, Atlanta, Ga., a corporation of Georgia

Application August 27, 1948, Serial No. 148,334

Term of patent 7 years

(Cl. D59—6)

To all whom it may concern:

Be it known that I, John H. Harland, a citizen of the United States of America, residing at Atlanta, in the county of Fulton, State of Georgia, have invented a new, original, and ornamental Design for Safety Paper or Article of Similar Nature, of which the following is a specification, reference being had to the accompanying drawing, forming part thereof.

The figure is a plan view of a piece of safety paper, showing my new design.

I claim:

The ornamental design for safety paper or article of similar nature, as shown.

JOHN H. HARLAND.
